UNITED STATES PATENT OFFICE.

HARRY O. SPENCER, OF CINCINNATI, OHIO.

COMBINATION VALVE DEVICE.

1,427,239.

Specification of Letters Patent. Patented Aug. 29, 1922.

Application filed November 30, 1921. Serial No. 518,978.

To all whom it may concern:

Be it known that I, HARRY O. SPENCER, a citizen of the United States, residing at Cincinnati, in the county of Hamilton and 5 State of Ohio, have invented certain new and useful Improvements in Combination Valve Devices, of which the following is a specification.

My invention relates to a combination 10 valve device, for use in connection with internal combustion engines, particularly such engines as are employed to drive automobiles, although not necessarily restricted to this use.

15 An important object of the invention is to provide a valve device of the character described, which will be very difficult to operate without a knowledge of the combination, which will not leak, is easy to adjust, 20 simple in construction, and cheap to manufacture.

Other objects and advantages of the invention will be apparent during the course of the following description.

25 In the accompanying drawings, forming a part of this specification, and in which like numerals are employed to designate like parts throughout the same,

Fig. 1 is a central vertical section view 30 through a valve device embodying my invention.

Fig. 2 is a plan view of the same, and,

Fig. 3 is a bottom plan view of the device.

In the drawings, wherein for the purpose 35 of illustration is shown a preferred embodiment of my invention, the numeral 5 designates a casing provided with oppositely arranged threaded nipples or tubular extensions 6, having their bores in communication 40 with ports 7 and 8, as shown. The nipples 6 are adapted to be connected in the gasoline supply pipe leading to the intake of the carburetor, and if desired, the casing may be arranged near the carburetor, while of course the invention is not restricted to this 45 particular location. The casing 5 is cylindrical and is provided at its top with a horizontal annular flange 9, forming a shoulder 10. Arranged within the casing 5 in concentric relation is an inner rotatable 50 valve 11, and cylindrical tubular valves 12 and 13. These valves interfit, and the outermost tubular valve 13 slidably contacts with the inner wall of the casing 5. The outer 55 tubular valve 13 is provided with a reduced tubular extension 14, forming a shoulder 15,

and packing 16 is arranged between the shoulder 15 and the shoulder 10. The tubular extension 14 projects through the opening 10 and extends upwardly above the 60 flange 9. The intermediate tubular valve 12 is provided with an upstanding tubular extension 17, forming a shoulder 18, arranged beneath a shoulder 19, and packing 20 is arranged between the shoulders 18 and 65 19. The tubular extension 17 projects through and beyond the tubular extension 14, as shown. The inner valve 11 is provided with a reduced extension 20', forming a shoulder 21, arranged beneath a 70 shoulder 22, and having packing 23 disposed between these shoulders. The extension 20 projects through and above the tubular extension 17, as shown. The tubular valve 13 has a pair of diametrically 75 oppositely arranged openings or ports 22, adapted to register with the bores 7 and 8. The tubular valve 12 has a pair of diametrically oppositely arranged ports 23, adapted to register with the ports 22 and 80 24, extending diametrically through the valve 11.

The numeral 25 designates a head or cap, secured to the casing 5 by screws 26 or the like. This head is provided centrally thereof 85 with a screw threaded opening 26', receiving a screw-threaded adjusting bolt 27 having a winged head 28. The inner rounded end of this bolt operates within a recess 29 in a follower element or plate 30, slidably 90 mounted within the casing 5. This follower plate is adapted to force the circular packing element or plate 31 into contact with the ends of the several valves, and also to force the shoulders of these valves, and their 95 several packing elements into firm engagement. This provides a positive means for preventing leakage, without binding of the valves, which are all cylindrical and do not taper.

100 The tubular extension 14 of the tubular valve 13 has an annular cap 31' arranged thereon, which cap is U-shaped in cross section. The cap is secured to the extension by round head screws 32, which form a convenient grip for the fingers. The cap 31' and the flange 9 are provided with numerals 33, to be used in operating the combination. The numerals 34 and 35 are caps secured to the extensions 17 and 20', and are identical 110 with the cap 31', except that they are of smaller diameter.

In operation, the caps 31, 34 and 35 are secured to their extensions, in such a manner that when selected numerals of the several caps and the flange 9 are brought into registration, such as V V V V, the several ports of the valves will be in registration with each other and with the bores 8. The gasoline is thus free to flow through the device. It is obvious that the combination 10 may be readily changed by circumferentially adjusting the cap with respect to its valve extension.

It is to be understood that the form of my invention herewith shown and described, is to be taken as a preferred example of the same, and that various changes in the shape, size, and arrangement of parts may be resorted to without departing from the spirit of my invention or the scope of the 20 subjoined claims.

Having thus described my invention, I claim:

1. A combination valve device comprising, a casing having inlet and outlet openings, said casing being provided at one end with an inwardly extending flange forming a main opening and a shoulder, a tubular valve rotatively mounted within the casing and having openings adapted to register with the inlet and outlet openings, said tubular valve being provided at one end with a reduced tubular extension extending through the main opening and forming a shoulder arranged beneath the first named shoulder, packing disposed between said shoulders, a valve rotatable within the tubular valve and having an opening adapted to register with the openings of the tubular valve, said valve having a reduced portion extending 40 through the tubular extension of the tubular valve and having a shoulder arranged beneath the interior shoulder of the tubular valve, packing disposed between the last named shoulders, means for indicating a 45 combination whereby the valves may be shifted to a position to bring all of the openings into registration, a follower plate arranged beneath said valves, a packing plate arranged between the follower plate and

and valves, and adjustable means to move 50 the follower plate toward the valves.

2. A combination valve device comprising, a casing provided with inlet and outlet openings, said casing being provided at one end with an inwardly extending flange forming 55 a main opening and an internal shoulder, a tubular valve rotatable within the casing and having openings adapted to register with the openings of the casing, said tubular valve having a reduced tubular extension 60 projecting through the main opening and forming interior and exterior flanges, packing arranged between the exterior flange of the tubular valve and the flange of the casing, a second tubular valve rotatable within 65 the first named tubular valve and having openings adapted for registration with the openings of the same, said second tubular valve having a tubular extension projecting through the tubular extension of the first 70 tubular valve and forming interior and exterior shoulders, packing arranged between the exterior shoulder of the second tubular valve and the interior shoulder of the first tubular valve, a valve rotatable within the 75 second tubular valve and having an opening adapted to register with the openings thereof, the last named valve having an extension projecting through the tubular extension of the second tubular valve and forming a 80 shoulder, packing arranged between the last named shoulder and the interior shoulder of the second tubular valve, said extensions having reference characters whereby a known combination may be produced so that 85 all of said openings will be in registration, a head secured to the opposite end of the casing and having a screw threaded opening, a follower plate arranged between the head and the ends of said valves, a packing plate 90 arranged between the follower plate and said valves, and an adjusting bolt operating within the screw threaded opening of the head and contacting with said follower plate. 95

In testimony whereof I affix my signature.

HARRY O. SPENCER.
